COLANDER

James B. Swett, Barrington, R.I., assignor to Rexall Drug and Chemical Company, Los Angeles, Calif., a corporation of Delaware

Filed May 8, 1964, Ser. No. 79,887

Term of patent 14 years

(Cl. D44—15)

FIG. 1

The essential feature of the design resides in the particular pattern and arrangement of the perforations shown.

This is a continuation-in-part of my earlier application Serial No. D. 69,200, filed March 12, 1962 and now abandoned.

I claim:

The ornamental design for a colander, as shown and described.
